UNITED STATES PATENT OFFICE

ARVID P. EKVALL, OF WORCESTER, MASSACHUSETTS, ASSIGNOR TO ECONOMIC MACHINERY COMPANY, OF WORCESTER, MASSACHUSETTS, A CORPORATION OF MASSACHUSETTS

LABEL WIPER

Application filed February 27, 1928. Serial No. 257,815.

This invention relates to a label wiping mechanism which is adapted to work in conjunction with the labelling machine as described in my prior Patent No. 1,630,235, issued May 24, 1927. Generally speaking, in machines of the type just mentioned, it has been found that the lateral edges of the label are not firmly and securely affixed to the bottle or object being labelled, and it is, therefore, the main feature of this present improvement to remedy this defect.

Another object of the invention resides in the manner in which the bottle or object is gripped or clamped between two carrying members and while in this gripped or clamped position the bottle or object is positively carried past and subjected to the action of a label wiping mechanism.

A further object of the present invention is the provision of an adjustment for the label wiping mechanism wherein said mechanism may be caused to coact with bottles or objects of various sizes and shapes.

A still further object of the present improvement resides in the novel and efficient manner of causing inward movement of the oppositely disposed wipers by which movement the wipers are positively caused to follow the contour or shape of the article being labelled.

While in the foregoing I have briefly described some of the objects of the present invention, it will be readily understood that others will be suggested to persons skilled in this particular line of apparatus and that certain changes in construction may be resorted to without sacrificing any of the spirit of the invention. Also in the accompanying drawings I have shown, and in this specification I have described the application of a label to a bottle, it will be realized that other objects or articles may be treated or handled in a like manner. The drawings should, therefore, be considered merely as illustrative and not in a limiting sense whatsoever so long as the structure falls within the scope of the appended claims.

In the drawings similar letters of reference indicate like parts throughout the several views wherein—

Figure 1 is a rear elevation of the label wiping mechanism with parts broken away to more clearly set forth the operating features of the wipers.

Figure 2 is a side view of the mechanism at the label wiping station in the machine.

Figure 3 is a top plan view of the showing made in Figure 2.

Figures 4, 5 and 6 are enlarged detail views of the lever which is adapted to actuate the label wipers.

Figure 7 is an enlarged view of the label wiping members.

In making specific reference to the drawings 1 designates the machine base or bed upon which all of the various stations of the apparatus are mounted. As in my prior machine I use a step by step conveyor 2 for carrying the bottles past the several operative stations and laterally offset from the exit end of this conveyor I also arrange a delivery belt or carrier 3. Aligned with the exit end of the step by step conveyor 2 is a vertical standing plate or frame 4 upon which is mounted the mechanism for carrying bottles past the label wiping station and finally delivering said bottles to the delivery belt or carrier 3. As in my prior patent this bottle clamping mechanism comprises a pair of reciprocatingly actuated bars or slides 5—6 each being suitably supported by guide straps 7—7. The slide 5 is actuated through a toggle and link connection to the pivoted arm 8, while the slide 6 is similarly operated through connections with pivoted arm 9. Each of the arms 8 and 9 have intermediate the ends thereof a roller 10. The roller on the arm 8 is in operative engagement with a cam 11 while the roller on the arm 9 coacts with a cam 12, both of said cams being rigidly secured to a power drive shaft 13. Suitable springs 14 are used to effectively hold the rollers 10 into contacting positions on the cams 11 and 12. All of this structure is shown in my prior patent and no claim is made thereto in the present case.

To the forward end of the slide 6 is secured a pusher 15 which is provided with deflected fingers or arms 16—16 to slightly embrace or form a seat for the bottle. The

forward end of the slide 5 carries a depending arm 18 to the lower end of which is secured a yieldable pad 19 in opposite facing relation to the pusher 15 to firmly hold the bottle in a clamped position.

In my former patent the coaction of the pusher and the forward grip was to smoothly attach the label to the bottle, but this is not the case here as the said members have a 10 relatively small surface engagement with the bottle, in fact just sufficient to firmly grasp and hold the bottle during a subsequent movement, or in other words, while the bottle is being pushed through the labelling 15 wiping station of the machine.

Between the exit end of the step by step feed 2 and the inlet end of the delivery belt 3 is positioned the label applying mechanism which in the present improvement comprises 20 a pair of oppositely disposed pads or wipers 20—20. These pads in their normal position are arranged to slightly overlap the forward face of the bottle during the initial entry of the bottle into the wiping station and are 25 thereafter caused to follow the side contours and slightly around the back of a bottle during its transit through the wiping station. In order to accomplish this traversing movement of the wipers 20—20 around the bottle, 30 the said pads are each mounted on oppositely actuated members which operate in timed unison with the balance of the machine.

On the machine base or bed 1 and extending longitudinally thereof is positioned a 35 plate or frame 21 and extending across the top of this plate is a rod 22. Slidably mounted on the rod 22 is a pair of oppositely actuated members 23—23, each of said members having an upstanding portion 24 and a depending arm 25. The lower extremity of the arms 25 extend within a guide 26, thus preventing the member 23 from having any pivotal action or movement on the rod 22. The upstanding portions 24 are slightly recessed 40 to receive the wiping pads 20. These pads are removably secured in position by any suitable connection as suggested at 27—27 and in order to add tension to the pads through their wiping coaction with the bottle a flat spring blade 28 is associated with 45 each of them. Pivottally secured to the plate 21 is a pair of bell cranks 29—29, the upper arm of each being connected through a link 30—30 to one of the slidable members 23—23. 50 The opposite arm of each bell crank is pivotally connected to a cross arm 31 through the link connections 32—32. The cross arm 31 is rigidly secured to the reciprocating rod 33 which is retained in its true vertical 55 position by the guide eye 34.

Rigidly secured to the power shaft between the cams 11 and 12 is a double cam 35 either of which is adapted to actuate the wipers 20 through the employment of the pivoted 60 lever 36 carrying roller 37 and having a piv-

oted link connection 38 with the reciprocal rod 33. The roller 37 is held in active position on the periphery of the selected cam by tension spring 39. The lever 36 has a laterally extending shaft 40 on which the roller 37 is mounted, the length of said shaft being at least equal to the distance between the cams on double cam 35. The lever 36 also has a vertically extending stub shaft 41, on which is pivotally mounted an arm 42, the forward end of this arm being split or bifurcated as at 43 to straddle the roller 37 while the rear end of the arm is provided with a clamping stud 44 or similar device. The rear end of the lever 36 is slotted as at 45 to receive the stud 44. When it is desired to shift the roller 37 so that the same will have operative engagement with the opposite cam, the fastening stud 44 is loosened and the arm 42 is moved about its pivot, this causing a shifting action of the roller 37 along the shaft 40 after which the arm 42 is again locked against movement by the fastening stud 44.

When the bottles arrive at the exit end of the conveyor 2, the label has only been partially applied thereto. As in my prior patent the lateral edges are still free and unattached to the surface of the bottle. At this exit end of conveyor 2 the bottle is grasped or gripped by the pusher 15 and the depending finger 18 and in this secured position it is projected forward. The wipers 20 are extended sufficiently to project into the path of movement of the bottle and will, therefore, come in contact with the label on opposite sides of the secured center and during the continued forward movement of the bottle, said wipers will bend or flex which effectively smoothes and presses the label on to the forward portion of the bottle. During all of the action just described the wipers have been merely flexed from their normal straight position, no movement whatsoever having been given to the wiper carrying arms. The affixing of the ends of the label is attended to by the inward movements of the slidable members 23—23 which carry the wipers 20—20. During this inward movement the wipers are subjected to a pulling action created by the advancing bottle and also to a pushing action caused by the inward movement of the slidable members 23, such actions resulting in extreme flexing of the wipers. To assist the wipers when this occurs the spring blades 28—28 come into action and add their force to the pads to enable them to firmly affix the extreme edges of the label to the rear face of the bottle.

The bottle shown in the drawings is of the round type, but the machine is capable of taking care of a bottle or article of different shape. For instance a rectangular or square bottle may be treated and in such case the roller 37 on the pivoted lever 36 is adjusted

to actively engage the opposite cam. This will cause a different range and speed of movement to the wipers to properly accomplish the affixing of the lateral ends of the label.

5. What I claim is:

1. A label wiping mechanism comprising a pair of oppositely disposed slidable wipers, positive actuated means for advancing said wipers towards each other, and means for feeding a bottle with a partially applied label to the action of said wipers during the advancing sliding movements of the latter.

10. 2. In a label wiping mechanism, a plurality of cams for operating said mechanism, and means for selectively actuating said wiping mechanism from either of said cams.

15. 3. In a label wiping mechanism, a pair of oppositely disposed label wiping elements adapted for coaction with the lateral edges of a partially applied label, a plurality of actuated cams, and means for selectively actuating the wiping elements from either of said cams.

20. 4. In a label wiping mechanism, a pair of oppositely disposed slidable wipers adapted for coaction with the lateral edges of a partially applied label, a plurality of actuating means for slidably operating said wipers, and means for selecting one of said actuating means for determining the operation of said wipers.

25. 5. In a label wiping mechanism, a pair of oppositely disposed label wiping elements adapted for coaction with the lateral edges of a partially applied label, a plurality of actuated cams, a lever having an adjustable roller thereon adapted for coaction with either of said cams, means for retaining said roller in its desired adjusted position and an operative connection between the lever and the wiping elements.

30. 6. In a label wiping mechanism comprising a pair of oppositely disposed slidable wipers, means for advancing a bottle with a partially applied label thereon between said wipers, and a positive actuated means for simultaneously sliding said wipers toward each other during the advancement of the bottle between said wipers.

35. 7. In a label wiping mechanism comprising a pair of oppositely disposed wipers, means for advancing a bottle with a partially applied label thereon between said wipers, and a positive actuated means for simultaneously sliding said wipers relative to the surface of the bottle during the advancement of the bottle between said wipers.

40. 8. In a label wiping mechanism comprising a pair of oppositely disposed flexible wipers, means for advancing a bottle with a partially applied label thereon between said wipers to initially flex said wipers, and

45. 9. pers towards each other to maintain said wipers in a flexed condition.

50. 9. In a label wiping mechanism comprising a pair of oppositely disposed slidable members, a flexible wiping pad carried by each of said slidable members, means for advancing a bottle with a partially applied label thereon between said slidable members thereby flexing said wiping pads to one side of their axial alinement, and positive actuated means for moving said slidable members to maintain in a flexed position during the advancement of the bottle to press the ends of the label on to the surface of the bottle.

55. 10. In testimony whereof I hereunto affix my signature.

ARVID P. EKVALL.
